CONTAINER AND CLOSURE THEREFOR

Reco Capey, New York, N. Y., assignor to Yardley of London, Inc., Union City, N. J., a corporation of New Jersey

Application August 28, 1945, Serial No. 613,059

2 Claims. (Cl. 222—545)

1

The present invention relates to containers for powdered materials and more particularly, though not necessarily exclusively, to improvements in powder dispensing means and closures therefor.

In accordance with the present invention, a novel and improved closure for the dispensing openings in a powder container is provided. Also, in accordance with the invention, the container is improved and its construction and arrangement is very much simplified whereby to promote ease and economy of container manufacture. A closure device constructed in accordance with the invention is capable of being constructed of an easily worked material, such as thin sheet metal and may be produced by a minimum number of forming operations.

Accordingly, the primary object is to provide a novel dispensing container for powdered material.

Another object is to provide a simplified container for dispensing powdered materials which may be provided with a readily constructed closure arrangement.

A further object is to provide a novel and improved closure for the dispensing opening or openings of a powder container.

A still further object is to provide a dispensing container for talcum powder or the like in which the dispensing openings are in a side wall of the container rather than in the top thereof.

Other objects and advantages of the invention will, of course, become apparent and immediately suggest themselves to those skilled in the art to which the invention is directed from a reading of the following specification in connection with the accompanying drawings in which:

Fig. 1 is a view in elevation of a dispensing container constructed in accordance with the invention;

Fig. 2 is a view in elevation of a portion of a closure arrangement constructed in accordance with the invention;

Fig. 3 is a view from beneath of the closure part of Fig. 2;

Fig. 4 is a view in elevation of the second portion of the closure arrangement;

Fig. 5 is a view in plan of the closure part of Fig. 4;

Fig. 6 is a view in elevation of a closure part for a modified closure arrangement in accordance with the invention;

Fig. 7 is a view from beneath of the closure part of Fig. 6;

Fig. 8 is a view in elevation of a second portion

2

of the closure arrangement to suit the modified form of Fig. 6; and

Fig. 9 is a view from beneath of the closure part of Fig. 8.

Figs. 1 to 5 of the drawings are arranged so that the parts are illustrated in the order of assembly, and therefore, these figures of the drawing may be understood as comprising an exploded view of a dispensing container embodying the invention in one form. Referring for the present to Figs. 1 to 5 of the drawings and now more particularly to Fig. 1 thereof, 10 indicates a container such as may be used to hold material in powder form such as talcum powder or other cosmetic material in powder form. The container 10 may be of any desired shape and may be made of any material, such as plastic or thin metal. The dispensing and filling end 12 of the container 10, which is most commonly the top of the container, 10 is provided with a filling opening 14 in the end or top wall of the container and a dispensing slot 16. It will be understood that the dispensing slot 16 may be replaced by a series of spaced holes, since neither the slot 16 nor any other aperture in the container 10 is relied on to hold the closure parts to be described in position on the container.

The closure part 18 (Figs. 2 and 3) is substantially cup-shaped, as shown, to conform to the end 12 of the container 10 and may be constructed of plastic or thin sheet metal. The closure part 18 is frictionally held on the end 12 of the container so that openings 21 therein register with the container opening 16. It will be understood that in place of spaced holes or openings 21, a slot of any desired shape may be formed in the closure part 18 so as to register with the slot 16 in the container end 12.

Depending skirt portions 23 and 24, one of which appears in Fig. 2, are provided so as to limit movement of the outer nested closure part 26 shown in detail in Figs. 4 and 5 of the drawings.

The outer closure part 26 which, as stated, nests over the closure part 18, is provided with a slot or opening 28 which may be brought into register with the openings 21 and the slot 16 at will. The outer closure part 26, like the other parts heretofore described, may be formed of any desired material, such as plastic or thin sheet metal, and is provided with protuberances 31 and 32 which lie just beneath the lower edge 34 of the part 18 in the assembled relationship of the parts so as to maintain the closure part 26 in assembled position on the part 18. The edges 36 of the skirt portions 23 and 24 serve as stops for the

outer closure part 26 to limit its range of movement from a fully closed position of the dispensing slot 16 to a fully open position. If desired, the outer closure part 26 may be provided with a flaring flange or skirt 38 which registers with and covers an enlarged portion 39 at the end of the container.

From the foregoing it will be understood that when the parts are assembled to the container 10 in the order in which they are shown on the left hand side of the drawings, a compact side dispensing arrangement for the container 10 is provided.

Figs. 6 to 9 of the drawings disclose a modified form or the invention as applied to the closure parts. The container 10, arranged as shown in Fig. 1, receives the modified closure members of Figs. 7 to 9 as well as the closure members of Figs. 2 to 5.

The inner closure member 42 shown in Fig. 6 is substantially cup-shaped so as to fit over the end 12 of the container 10 with openings 43 in register with the slot 16. A slot 46 in the closure part 42 serves in cooperation with protuberances 48 and 49 (Fig. 9) in the outer closure part 51 to limit the range of movement of this outer closure part.

The inner closure part 42 is nested within outer closure part 51 with the protuberances 48 and 49 accommodated by the slot 46. A slot 53 registers with the dusting holes 43, and in turn, with the slot 16 in the end 12 of the container 10 when the outer closure part 51 is turned to one extreme limit of its range of movement. When it is turned to the other extreme limit of its range of movement, the slot 53 no longer registers with the dusting opening 43.

From the foregoing, it will be seen that this invention provides a dispensing container of simplified form and few parts which may be readily assembled after the container has been filled with the powdered material to be dispensed. Also, it is to be noted that in accordance with the illustrative embodiment shown herein by way of example, that the invention provides for the use of parts which may be readily and cheaply manufactured.

Having now described the invention, what is claimed and desired to be secured by Letters Patent is the following:

1. A dispensing device comprising, a container

having a neck provided with an end filling opening and a dispensing opening in its side wall, a cup-shaped skirted closure member fitted over the neck, said closure member being provided with dispensing openings in its skirt alined with that provided in the side wall of the neck, the closure member having portions of its skirt cut away upwardly from its lower edge to provide spaced stop shoulders, the provision of said cut-away portions in the skirt resulting in forming the skirt with relatively wide and narrow portions, the apertures in the skirt being located in the wide portion of the skirt between the cut-away portions thereof, a second skirted cup-shaped closure member slidably fitted over the first closure member, said second member being provided with a dispensing opening in its skirt adapted to be either alined or disaligned with the openings in the first member, the second member having a skirt of substantially uniform height and sufficient to extend below the lower edge of the skirt on the first closure member, the skirt on the second closure member being provided with protuberances located above its lower edge and entering the cut-away portions of the first closure member to engage against the shoulders thereon to position the second member in one position or another.

2. A dispensing device as provided for in claim 1, wherein the first closure member is provided with a closed top, the cut-away portions of the skirt on said member being located diametrically opposite on the skirt, and the skirt on the second member being provided with two inwardly-extending protuberances, one of which is operative in each of the cut-away portions of the first closure member.

RECO CAPEY.
